DISTRIBUTOR GAUGE

Ernest Tooke, London, England

Application August 13, 1957, Serial No. 677,991

4 Claims. (Cl. 33—180)

This invention relates to a method of and means for setting the contact points of the distributor of an internal combustion engine. The usual method employed for setting the gap between the contact points of a distributor consists in slowly turning the engine over until a lobe on the cam of the distributor engages the heel of a spring loaded pivoted contact breaker and the gaps between the contact points of the distributor are fully open whereupon the necessary adjustment is effected to increase or decrease the gap. With internal combustion engines provided with a starting handle it is a simple matter to turn the engine over until the lobe of the cam and the heel of the contact breaker are in the requisite position, but with certain present day motor-cars a starting handle is not always available and it then becomes necessary to move the car, whilst in gear, to-and-fro until the heel of the contact breaker and lobe engages at a point where the contact points are held fully open. The object of the present invention is to provide a method of setting or adjusting contact points of a distributor which can be more quickly and effectively conducted than hitherto and at the same time will avoid the disadvantage where lack of a starting handle renders the operation difficult.

According to the invention a method of setting the contact points of a distributor consists in freeing the fixed contact support plate, shrouding the cam of the distributor with a cylindrical sleeve, introducing a limit gauge of a predetermined thickness between the contact of the breaker arm and the relatively fixed contact of the distributor, closing the contacts on the limit gauge, re-securing the contact breaker support plate and finally, removing the sleeve and limit gauge.

Preferably, the wall thickness of the sleeve and the limit gauge are co-related to give the correct gap between the contact points after adjustment and their removal.

The invention also includes means for setting the contact points of the distributor of an internal combustion engine comprising in combination a cylindrical sleeve having a predetermined wall thickness and a limit gauge also of a predetermined thickness, the two dimensions being related to give the required gap between the contact points of the distributor after setting by the means described. The sleeve and limit gauge are preferably anchored together by, for example, a short length of chain.

It will be appreciated that it is essential that there should be reasonably close fit between the sleeve and the cam, and that apparent play should not be present. It has been discovered, however, that cams for various types of distributors differ slightly in their overall dimensions and furthermore, wear, in the course of time, will effect such dimensions, the variation in the diameter of the different cams may vary as much as .006 of an inch. Accordingly, it is preferred that the sleeve should have a spring character whereby resilience is imparted thereto so that as a result cams of differing dimensions within comparatively narrow limits can be shrouded for the

purpose specified. To this end the sleeve is slit lengthwise and conveniently produced from hardened and tempered strip steel, one edge of which may be quarter rounded to form a grip.

5 Alternatively, the entry end of this sleeve is slit to approximately half its length, the slit extending from the entry end of the sleeve and terminating in an arcuate slit extending partly around the circumference of the sleeve. The slit can be of T-or-L form in elevation and 10 provides a double flap of spring character to the lower part of the sleeve in the first instant and a single spring flap in the second instant.

The invention also is directed to a method of producing a sleeve according to the foregoing paragraph, consisting in rolling a length of strip spring steel, one edge of which may be beaded or radiused, into a longitudinally slit sleeve, subsequently hardened and tempered.

The device according to the invention will hereinafter be referred to as an "ignition gauge."

In order that the invention may be clearly understood and readily carried into effect, reference is directed to the accompanying drawing, wherein:

Figure 1 shows in side elevation an ignition gauge according to the invention.

Figure 2 is a section on the line II—II of Figure 1.

Figure 3 is a side elevation of a modified form of sleeve.

Figure 4 shows in side elevation a modified form of ignition gauge according to the invention.

Figure 5 is a section on the line V—V of Figure 4, and

Figure 6 shows in elevation a simplified form of sleeve.

Referring to the drawing in general, the ignition gauge consists of a short length of metal tube constituting the sleeve *a* of the invention, conveniently with a highly polished internal and external surface of a definite wall thickness, for example, 0.25 of an inch, and a limit gauge *b* connected to the sleeve by a chain *c*. As shown in Figures 1, 2 and 3, one end of the sleeve *a* is circumferentially beaded as at *d* to form a convenient means of gripping the sleeve when being placed over the cam of a distributor, the internal dimensions of the sleeve being such as to frictionally engage the cam. The limit gauge *b* used in conjunction with the sleeve comprises a slip of metal of the desired thickness, i.e., .043 of an inch and suitably shaped for manipulation.

It will be appreciated that the sleeve need not have a predetermined wall thickness but in order to ensure the correct gap between the contacts of the distributor the limit gauge must have a thickness equivalent to the wall thickness of the sleeve, the dimensions of the desired gap, plus an additional wall dimension to neutralize the angular movement of the contact breaker arm when the sleeve is placed in position. For example, to obtain a 55 gap of 0.0015 a gauge of 0.0046 is needed with a sleeve thickness of 0.0025.

In order to impart additional resilience to the sleeve so that cams of relatively differing dimensions, with narrow limits, may be shrouded, the entry end of the sleeve 60 *a* is slit lengthwise for a part of its length or provided with an L-shaped slit *e* as shown in Figure 1, or a T-shaped slit *f* as shown in Fig. 3. Alternatively, the sleeve *a* may have a longitudinal slit *g* from top to bottom as shown in Figures 4 and 5 or 6, for the same purpose.

65 Figures 4 and 5 illustrate a construction in which the sleeve is provided with an outwardly turned upper edge *h* to facilitate its use. The sleeve *a* shown in Figures 4 and 6 is conveniently manufactured by rolling into shape from strip spring steel of the requisite dimension, being subsequently hardened and tempered.

In use the fixed contact plate of the distributor is made free from its base support by loosening its fixing

screws and the sleeve slipped over the cam of the distributor with the heel of the contact breaker abutting. The limit gauge is introduced between the two contact points which are closed thereon and the contact breaker support plate re-secured. Removal of the sleeve and the limit gauge will leave the contact points correctly set.

The spring means provided in the construction of the sleeve enables the latter to be held resiliently to the cam and closely engaged therewith, it being understood that the sleeve in addition to being usable for standard size cams can also be fitted to over or undersize cams within certain limits.

It will be appreciated that the invention is capable of use for multi-cylinder engines and although the sleeve and limit gauge are preferably made of metal, non-metallic substances may be used for their manufacture, such as one of the plastics, and, further, a number of single longitudinal slits may be formed in the sleeve or the T-or-L-shaped slits may be duplicated at opposite sides of the sleeve, or alternatively, the sleeve may be quite plain and unslit.

What I claim and desire to secure by Letters Patent is:

1. An ignition gauge for adjusting the setting of the contact points of the distributor of an internal combustion engine having a breaker cam and follower comprising, in combination, a cylindrical sleeve having a wall of uniform thickness for supported engagement upon the breaker cam of the distributor adjacent to the follower of the breaker unit, said wall having opposite end edges and defining a slit therebetween, said slit extending from one of said edges toward and spaced inwardly from the other one of said edges, the outside diameter of said one edge of said sleeve communicating with said slit being adjustable to conform substantially to the diameter of the breaker cam of the distributor, and said opposite edge of said sleeve being of substantially constant diameter so as to retain frictionally said sleeve upon the breaker cam of the distributor.

2. An ignition gauge for adjusting the setting of a distributor having contact points controlled by the move-

ment of a breaker cam and follower, comprising a cylindrical sleeve having a flexible side wall of substantially uniform thickness for slidably engagement upon the breaker cam of the distributor to be adjusted, said side wall having longitudinally spaced apart terminal edges, portions of said side wall defining a slit communicating with one of said terminal edges and extending partially toward the opposite terminal edge of said side wall, the outside diameter of said one edge of said side wall being adjustable to conform substantially to the sides of a circle circumscribed by the breaker points of the breaker cam, and said opposite terminal edge of said side wall being of substantially constant diameter frictionally receiving the breaker cam longitudinally therewithin removably to secure said sleeve upon the breaker cam.

3. An ignition gauge for adjusting the setting of the distributor contact points as set forth in claim 2 wherein said slit is of substantially L-shaped configuration having one leg extending perpendicularly inwardly from said one terminal edge of said wall, and a perpendicularly related leg of said L-shaped slit extending parallel to and spaced inwardly from said opposite terminal edge of said side wall.

4. An ignition gauge for adjusting the setting of the distributor contact points as set forth in claim 2, wherein said slit is of substantially T-shaped configuration having one base leg extending perpendicularly inwardly from said one terminal edge of said side wall, and a perpendicularly related cross leg of said T-shaped slit extending parallel to and being spaced inwardly from said opposite terminal edge of each side wall.
